UNITED STATES PATENT OFFICE

GEORGE T. HART, JR., OF WEST LYNN, MASSACHUSETTS, ASSIGNOR TO UNITED SHOE MACHINERY CORPORATION, OF PATERSON, NEW JERSEY, A CORPORATION OF NEW JERSEY

SEWING MACHINE

Application filed December 12, 1930. Serial No. 501,847.

The present invention relates to machines for sewing soles to the uppers of boots and shoes, and particularly to that class known as McKay sewing machines in which a hook 5 needle penetrates the sole and enters the interior of the shoe and a horn is introduced into the shoe for supporting the same and for conducting the thread to the sewing point.

In machines of this type it is customary to 10 thread the needle by means of a needle threading whirl or looper rotatably mounted in the tip of the horn and having motion imparted thereto from the sewing cam shaft in the head of the machine by gear actuated 15 mechanism, gear teeth being cut in the periphery of the whirl to provide a connection with said mechanism. While the whirl used in such machines has been reduced to the smallest possible dimensions, the 20 tip of the horn is still objectionably large for some types of work and this situation is unavoidable in machines employing a rotary whirl for threading the needle. In order to permit the use of horns with smaller tips 25 than have heretofore been possible, the present invention has eliminated the needle threading whirl and provided in its place a novel needle threading mechanism having no moving parts and actuating mechanism 30 therefor positioned in the horn.

The novel needle threading mechanism comprises a horn having an opening for the passage of the thread and for the reception of the needle point, and means for rotating 35 the needle at the limit of its downward stroke in order to cause the needle to engage the thread and carry it about the needle in order to lay a loop of thread in the needle barb. The needle is provided with a thread engaging 40 surface in the form of one of the usual vertical grooves extending from the open eye towards the point of the needle, and the opening in the horn is of a size to closely fit the needle so that the thread is confined within 45 the thread engaging groove during the rotation of the needle.

Another feature of the invention consists 50 of a loop spreader for insuring the entrance of the needle into the thread loop during its downward stroke. In the present embodiment

of the invention the loop spreader consists of a cam actuated finger adapted to engage the forward leg of the thread loop and hold it distended as the needle commences its downward stroke. 55

Other features of the invention consist of the novel constructions, combinations and arrangements of parts hereinafter described and claimed, the advantages of which will be understood by those skilled in the art from 60 the following description.

Referring to the accompanying drawings illustrating the invention in its preferred form, Fig. 1 is a front elevation of a chain-stitch sewing machine having my invention 65 embodied therein, so much only of the machine being shown as is necessary to an understanding of my invention; Fig. 2 is a side elevation showing the parts in the same position as in Fig. 1; Fig. 3 is a sectional plan 70 view taken on the line 3—3 of Fig. 1; Figs. 4, 5 and 6 are vertical sections of the horn illustrating the needle and thread in three positions during the needle's rotation; Fig. 7 is a sectional plan view taken on the line 75 7—7 of Fig. 4; Fig. 8 is a sectional plan view taken on the line 8—8 of Fig. 6; and Fig. 9 is a sectional elevation taken on the line 9—9 of Fig. 1, several parts being omitted. 80

The drawings illustrate a shoe sewing machine such as that described in the patent to E. P. Richardson No. 710,612, dated October 7, 1902, to which patent reference may be had for all features of the machine not herein illustrated. Machines of this type employ a 85 straight barbed needle operated by crank connections with a horizontal driving shaft extending longitudinally of the machine. The work is supported between a fixed horn and a spring and cam actuated presser foot 90 automatically adjustable for variations in thickness of work. The lower limit of the movement of the needle is constant but the upper limit of movement is varied in proportion to variations in thickness of the work 95 in order to cause the needle to draw through the work the exact amount of thread required for the formation of the stitch. Such variation in needle movement is effected through connections between the needle and the presser 100

er foot. In order to provide sufficient time for threading the needle, a period of lost motion is provided at the lower limit of the movement of the needle.

Heretofore such machines have employed a needle threading whirl or looper rotatably mounted in the tip of the horn. As has been stated, an important feature of the present invention comprises a needle threading mechanism which requires no moving parts and actuating mechanism within the horn. As herein illustrated, this needle threading mechanism consists of the rotatable needle 10 mounted in a chuck 12 and secured therein by means of the set screw 14 and of a block 15 mounted in an opening in the horn 17 and held against upward movement by means of the cap 19 secured to the upper surface of the horn which block has a central perforation 21 for the reception of the point of the needle and for the passage of the thread from the supply to the work. The use of the block 15 does away with the needle threading whirl and the whirl actuating mechanism thus simplifying the machine and permitting the use of a horn having a smaller tip than has heretofore been possible. The chuck 12 is supported within the tubular member 16 which is brazed to the reduced lower portion 20 of the needle bar 18. The needle is rotated by the rack-actuated pinion 24 fixed to the shank 26 of the chuck and held in its position on the shank 26 between the shoulder 28 formed in said shank and the nut 22. The upper portion 36 of the shank 26 is reduced to permit the nut 22 to pass freely over it. The pinion 24 is held against rotation on the shank 26 by means of a pin 30 driven through said shank. The lower end 40 of the pinion 24 bears freely upon the upper surface of a cap 32 threaded to the lower end of the tubular member 16, and cooperates with the shoulder 33 formed in the chuck to maintain the chuck in its vertical relation to the tubular member. The shank 26 is journaled in bearings in the cap 32 and in the reduced lower portion 20 of the needle bar 18. Oil is delivered to the bearing surfaces of the chuck shank 26 and pinion 24 through an oil hole 38 in the needle bar 18.

The pinion 24 is actuated by the rack 40, said rack and pinion having an idler 42 inserted between them in order to space them apart from each other, said idler being rotatably secured to the machine frame by the screw 43. The tubular member 16 is open at the rear thereof to permit the idler 42 to engage the pinion 24 (see Fig. 3). The rack 40 is supported within a guideway 44 formed in a bracket 46 supported by the screws 48 and 50 threaded to the under side of the head of the machine. An oscillating motion is imparted to the rack 40 by means of the cam 52 fixed to the cam shaft 54, said cam actuating the cam lever 56 pivoted on the shaft 58,

which shaft is fixed to the extension 59 of the machine frame by means of a set screw 60. The cam lever 56 has a roll 62 fixed to the upper end thereof which roll bears upon the cam 52 and another roll 64 at the lower end 70 thereof positioned within a recess 66 formed in the lateral extension 68 of the rack 40, said roll 64 being supported laterally between the lever 56 and the inner surface of the recess 66. The length of movement of the rack 75 40 is sufficient to rotate the needle 10 approximately 270 degrees and the movements of the rack 40 are so timed that the needle is rotated 270 degrees in a clockwise direction, looking down at the needle, at the beginning 80 of its downward stroke, and 270 degrees in counter-clockwise direction while the barb of the needle is positioned within the horn. The latter rotation of the needle takes place during the interval of lost motion when the needle is vertically at rest, and leaves the needle with its open eye facing opposite to the direction of feed whereby the feeding of the work will not tend to draw the loop from the eye of the needle. Referring again to the cam 52, the clockwise rotation of the needle will take place when the roll 62 is passing over the surface 70 of said cam, and the counter-clockwise rotation of the needle will take place when the roll 62 is passing over the surface 72 85 of said cam. The space 74 on the edge of the cam 52 between the surface 70 and 72 represents the interval of time when the needle is passing through the work, during which interval the needle must not rotate, as rotation of the needle during this interval would tend to cause the work to rotate with the needle. During the greater part of the interval of lost motion and during the upward stroke of 90 the needle which follows immediately after 100 said interval, the needle does not rotate. During this period of time, the roll 62 is passing over the surface 76 of the cam 52.

The roll 62 is held in engaging position with the cam 52 by means of a spring 78 coiled 105 about the shaft 58, one end of said spring being held between the collar 80 and the shaft 58, the other end engaging the extension 84 of the horizontal portion 86 of the cam lever 56.

The needle 10 is constructed so as to engage the thread during the counter-clockwise rotation at the end of its downward stroke. To this end the needle is provided with a thread engaging surface 88 in the form of one of the usual vertical grooves extending from the open eye toward the point of the needle (see Figs. 7 and 8). When the needle enters the horn at the end of its downward stroke, the needle barb 90 is in the position indicated by Fig. 4 and the thread will be positioned within the groove 88 in the surface of the needle. During the counter-clockwise rotation of the needle the groove 88 will engage the thread and carry the thread with it during 125 its 130

rotation. At the end of the counter-clockwise rotation of the needle, the needle and thread will be in the position indicated by Figure 6, the thread being positioned within the barb of the needle. It is obvious that upon the up-stroke of the needle the thread will be carried through the work by the needle.

It is important that the opening 92 in the horn within which the threading operation takes place be of the proper diameter. This opening must be large enough to permit the barb of the needle together with the thread to rotate freely therein and it must be small enough so that the thread will be held between the groove 88 and the wall of the opening 92, and prevented by said wall from passing out of the groove 88.

The clockwise rotation of the needle at the beginning of its downward stroke tends to carry the thread loop out of the path of the needle. In order to overcome this tendency and insure the entrance of the needle into the loop, the thread loop is spread open at the beginning of the downward stroke of the needle by means of a loop spreader at the end of a rod 96, which rod is pivoted at 97 to the bracket 98 fixed to the machine frame. An oscillating motion is imparted to the loop spreader 94 by means of a cam 100 fixed to the cam shaft 54, said cam actuating the cam lever 102, which lever in turn actuates the link 104 attached to the upper end of the rod 96. The cam lever 102 has a roll 106 rotatably mounted therein, which roll is held in engagement with the cam 100 by means of a spring 108 coiled about the shaft 110 which shaft is journaled to a bearing in the lateral extension 111 of the forward end of the machine frame and to a bearing (not illustrated) in the rear of the machine frame. The lever 102 is secured to the shaft 110 by means of the pin 112. One end of the coiled spring 108 is secured to the collar 114 fixed to the shaft 110. The other end of the coiled spring 108 bears upon a screw 116 fixed to the extension 111 of the machine frame. A lever 118 is fixed to the forward end of the shaft 110 by means of the pin 119 and has pivoted thereto at 120 the link 104, the other end of which link is rotatably mounted in a yoke 122 fixed to the upper end of the rod 96. The thread engaging movement of the loop spreader takes place when the cam roll 106 is passing over the cam surface 124, which takes place immediately after the needle has commenced its downward stroke, the loop spreader engaging the forward leg of the thread loop at approximately the point of time when the needle begins its clockwise rotation. The above described timing of the loop spreader is essential to its function since the thread would not be in position to be engaged by the loop spreader after the needle had completed a substantial part of its rotation. The loop spreader 94 returns to its

original position at that interval during the upward stroke of the needle when the needle engaging surface 125 of the cast-off 126 is horizontally in line with the loop spreader 94. It is essential that the cast-off be at this point in its upward movement during the movement of the loop spreader since the loop spreader brushes against the cast-off in its movement and would be caught between the cast-off and the needle if the cast-off had not reached the aforesaid point in its upward movement when the loop spreader passed in front of the needle on its return movement. During said return movement of the loop spreader, the cam roll 106 passes over the cam surface 128, which surface is made shorter and steeper than the cam surface 124 in order that the return movement of the loop spreader may be rapid. Return movement of the loop spreader must be rapid in order to insure its passing across the needle before the needle barb has reached a point of elevation above the level of the loop spreader, but not before the cast-off reaches a point in its upward movement where the needle engaging surface 125 of said cast-off will be horizontally in line with the loop spreader. It is essential that the loop spreader make its return movement not later than this exact instant of time in order that it may avoid contact with the thread.

What is claimed as the invention is:—

1. In a sewing machine, the combination with the other sewing devices of a straight hook needle provided with a thread engaging surface, a shoe receiving horn, an opening in the horn in line with the needle axis for the passage of the thread and for the reception of the point of the needle, means for rotating the needle on its axis at the limit of its downward stroke, and means for holding the thread in engagement with said thread engaging surface.

2. In a sewing machine, the combination with the other sewing devices of a straight hook needle provided with a thread engaging surface, a shoe receiving horn, an opening in the horn in line with the needle axis for the passage of the thread and for the reception of the point of the needle, means for rotating the needle on its axis at the limit of its downward stroke, and means for holding the thread in engagement with said thread engaging surface comprising a thread engaging surface formed in the horn.

3. In a sewing machine, the combination with the other sewing devices of a straight hook needle provided with a thread engaging surface, a shoe receiving horn, an opening in the horn in line with the needle axis for the passage of the thread and for the reception of the point of the needle, cam actuated means for rotating the needle on its axis at the limit of its downward stroke,

and means for holding the thread in engagement with said thread engaging surface.

4. In a sewing machine, the combination with the other sewing devices of a straight hook needle provided with a vertical thread engaging surface and positioned during its upward stroke with its hook pointing in a direction opposite the direction of feed, a shoe receiving horn, an opening in the horn in line with the needle axis for the passage of the thread and for the reception of the point of the needle, means for rotating the needle on its axis at the limit of its downward stroke, and means for holding the thread in engagement with said vertical thread engaging surface.

5. In a sewing machine, the combination with the other sewing devices of a straight hook needle provided with a thread engaging surface, a shoe receiving horn, an opening in the horn for the passage of the thread and for the reception of the point of the needle, means for rotating the needle at the limit of its downward stroke, and means for holding the thread in engagement with said thread engaging surface, and means for spreading the thread loop in order to cause the needle to enter the loop during its downward stroke.

6. In a sewing machine, the combination with the other sewing devices of a straight hook needle provided with a thread engaging surface, a shoe receiving horn, an opening in the horn for the passage of the thread and for the reception of the point of the needle, means for rotating the needle at the limit of its downward stroke, and means for holding the thread in engagement with said thread engaging surface, and a cam actuated finger for spreading the thread loop in order to cause the needle to enter the loop during its downward stroke.

7. In a sewing machine, the combination with the other sewing devices of a straight hook needle, circular in cross section provided with a thread engaging surface, a shoe receiving horn, a circular opening in the horn in line with the needle axis for the passage of the thread and for the reception of the needle in closely fitting relation, and means for rotating the needle on its axis at the limit of its downward stroke.

8. In a sewing machine, the combination with the other sewing devices of a straight hook needle provided with a thread engaging surface, a shoe receiving horn, an opening in the horn in line with the needle axis for the passage of the thread and for the reception of the point of the needle, means for rotating the needle on its axis at the limit of its downward stroke, and means for holding the thread in engagement with said thread engaging surface comprising a thread engaging surface formed in the horn, and means for imparting a reverse rotation to the needle at the beginning of its downward stroke.

9. In a sewing machine, the combination with the other sewing devices of a straight hook needle provided with a thread engaging surface, a shoe receiving horn, an opening in the horn in line with the needle axis for the passage of the thread and for the reception of the point of the needle, means for rotating the needle on its axis at the limit of its downward stroke to bring it to a position in which the hook points in a direction opposite to the direction of feed, means for holding the thread in engagement with said thread engaging surface comprising a thread engaging surface formed in the horn, and means for imparting a reverse rotation to the needle at the beginning of its downward stroke through substantially three fourths of a revolution.

In testimony whereof I have signed my name to this specification.
